(57) CLAIM

The ornamental design for a pet carrier backpack as shown and described.

DESCRIPTION

FIG. 1 is a perspective view of a pet carrier backpack showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of a portion of the pet carrier backpack shown within the area designated as 9 in FIG. 8. The broken lines in the figures are for the purposes of illustrating portions of the pet carrier backpack that form no part of the claimed design. The dot-dash broken lines encircling portions of the pet carrier backpack shown within the area designated as 9 in FIG. 8 and illustrated in enlarged view in FIG. 9 form no part of the claimed design.

1 Claim, 9 Drawing Sheets
